"Vesla Home 16 Inch Soft Close Undermount Drawer Slides" Dec. 19, 2020, Amazon.com, site visited Feb. 10, 2025: <https://www.amazon.com/VESLA-HOME-Undermount-Extension-Hardware-1/dp/B0B5X47SJC?th=1> (Year: 2020).*Primary Examiner — Sanjeev Paul*Assistant Examiner* — Rene H. Kadoo(74) *Attorney, Agent, or Firm* — Justin Lampel(57) **CLAIM**

The ornamental design for a drawer slide, as shown and described.

DESCRIPTION

FIG. 1 is a first perspective view of a drawer slide showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is an enlarged view of portion of FIG. 1;

FIG. 10 is an enlarged view of portion of FIG. 2;

FIG. 11 is another enlarged view of portion of FIG. 2; and, FIG. 12 is a view of the drawer slide in a used state.

The broken lines in the drawings depict portions of the drawer slide that form no part of the claimed design.

1 Claim, 12 Drawing Sheets(56)
